UNITED STATES PATENT OFFICE

2,512,449

AWL ATTACHMENT FOR SCREW DRIVERS

Louis A. Wieland, Pittsburgh, Pa.

Application November 1, 1946, Serial No. 707,071

2 Claims. (Cl. 145—1)

1

My invention relates to the driving of screws, and consists in a screw driver equipped with a device for use in forming a hole for the starting or reception of a screw nail to be driven.

Devices of this sort have hitherto been proposed, but they have either been too costly, or have been too slow and awkward in manipulation. More particularly, my invention consists in certain new and useful improvements in such a device which may be economically produced and applied to screw drivers of existing types, and which may be readily slid upon the shank of a screw driver between a position where it is serviceable for drilling a hole and a position where it is out of the way, to permit of normal use of the screw driver.

The invention will be understood upon reference to the accompanying drawings, in which:

Fig. 1 is a view in side elevation of a screw driver of conventional form, equipped with a device of my invention, the device being shown in position for drilling;

Fig. 2 is a fragmentary view of the screw driver as seen on a plane extending at ninety degrees to the plane of view of Fig. 1, and showing the device to larger scale but in the service position shown in Fig. 1;

Fig. 3 is a view comparable with Fig. 2, showing the device removed from service position;

Fig. 4 is a view, as seen at ninety degrees from Fig. 3, and showing the device fully removed into inactive position;

Fig. 5 is a sectional view, on the plane V—V of Fig. 2;

Fig. 6 is a view in perspective of the drilling bit of the device; and

Fig. 7 is a sectional view on the plane VII—VII of Fig. 4.

The illustrated embodiment of the invention comprises a slide upon the shank 2 of the screw driver the device of the invention is to serve. The slide advantageously comprises an arm or strap 3 of spring steel provided at one end with means, in the form of spring clips 4 integrally constructed with the arm 3, for slidably and rotatably engaging the device to the shank 2, while at the opposite end of the spring arm 3 a drill bit 5 is secured. The drill bit is formed of tool steel, including a pointed and sharp cornered awl portion, and a head portion including a recess or kerf 6 to receive the tip of the screw driver, as will presently appear. The bit-supporting end of the arm 3 is fashioned into a U-shaped portion 7 in which the head portion of

2

the drill bit is received, and secured by means of a pivot pin 8, it being noted that the pivot pin 8 provides an articular joint between the pointed and recessed portions of the bit, to provide for such slight angular movement of the bit relatively to the spring arm as may be necessary for the bit to align itself with the axis of the screw driver shank when arranged in drilling position, as shown in Figs. 1 and 2. The U-shaped portion 7 of the arm 3 is notched adjacent to the base of recess 6 in the bit or awl 5, whereby the tip 9 of the screw driver provides a rigid integration of the pivoted awl in service, as will be understood upon considering Fig. 2.

The drilling device is reciprocable upon the shank of the screw driver, whereby the device may be readily adjusted in service position, with the tip 9 of the screw driver nested tightly in the recess 6 in the bit. In such position the bit is firmly secured in axial alignment with the shank of the screw driver, it being noted that the spring clip 4 in such service position wedges upon the shank of the screw driver in the region 10 (Fig. 1) where it flares to the flattened portion 11 on which the tip 9 is formed. This wedging action is a feature of the design and proportioning of the device, and is valuable in insuring the security of the device in service position.

The manner in which the screw driver may be manipulated to cause the bit 5 to form a starting recess or a hole in the body in which a screw is to be driven hardly needs description. The point of the bit 5 is simply spotted at the point where a screw is to be driven; then, with the screw driver held in normal position over such point, the screw driver is pressed and turned, after the manner that an awl is manipulated. The sharp cornered, pyramidal pointed bit 5 of tool steel quickly forms the desired hole, whereupon the drilling device is moved from service position into inactive position (Figs. 3 and 4), in which it is out of the way to permit of the conventional use of the screw driver in driving the screw.

The readiness with which the device may be shifted between service and inactive positions is a feature of great practical value, since the user loses no appreciable time in his work; it is merely necessary to shift the device forward on the shank 2 until the screw driver tip 9 is free of the recess 6; then the arm 3 is pressed laterally, the elongate form and resilience of the arm 3 readily permitting this movement, and then the device is slid rearwardly on the shank 2, into the position in which it is shown in Fig.

3. Indeed, the device is usually moved further rearwardly on the shank 2 than Fig. 3 indicates, but this is a matter of choice with the user. In any position into which the device is removed from engagement with the tip 9, it is important to note that the spring arm 3, by virtue of its inherent elasticity, operates to clamp the bit 5 snugly against the screw driver shank, and Figs. 1 and 7 illustrate a depression 12 provided in the body of the bit, to provide for this desired snug engagement with the shank. Fig. 4 illustrates that when the device has been removed on the shank to a point where the bit 5 lies beyond the broadened portion 11 of the shank, the entire device may be rotated through 90 degrees, and greatest compactness or closest engagement of the bit with the shank obtained. In this position the pointed end of the bit is screened or guarded by the flared portion of the screw driver shank.

Various modifications and changes may be made in the exemplary structure illustrated and described herein, without departing from the spirit of the invention defined in the appended claims.

I claim:

1. For assembly with a screw driver, a device for forming a hole for the start of a screw to be driven comprising an arm, means for slidably securing said arm to the shank of a screw driver, a flange portion on said arm, a pyramidal sharp-cornered awl secured to said flange por-

tion on said arm, said awl and the adjacent flange portion of said arm being recessed to receive the tip of the screw driver, with the awl positioned in alignment with the axis of the screw driver shank, said arm being reciprocable on said shank for disengaging the awl from said tip and moving the awl into position against said shank, with the point of the awl directed toward the screw driver tip.

10 2. A device for attachment to a screw driver comprising an elongate spring arm flanged at one end and provided at opposite end with means for slidably engaging the shank of a screw driver, and an awl pivoted to the flanged end of said arm, said flanged end of said arm and said awl being recessed to receive the tip of said screw driver, with the pivot joint between the awl and the arm located between the point of the awl and tip-receiving recess therein.
